UNITED STATES PATENT OFFICE.

ALFRED F. MURPHY, OF MONTREAL, QUEBEC, CANADA.

VALVE.

1,271,062.

Specification of Letters Patent.

Patented July 2, 1918.

Application filed April 17, 1914. Serial No. 832,668.

To all whom it may concern:

Be it known that I, ALFRED F. MURPHY, a citizen of the United States of America, residing at the city of Montreal, in the Province of Quebec, and Dominion of Canada, have invented certain new and useful Improvements in Valves, of which the following is a full, clear, and exact description.

This invention relates to improvements in reducing valves, and the object is to provide a valve which may be adjusted to deliver a fluid at any predetermined pressure, regardless of the pressure of fluid supplied to the valve.

15 A further object is to provide a valve which will operate automatically to control the admission of fluid under varying high pressure, so that the fluid will be delivered from the valve at unvarying low pressure.

20 A still further object is to provide a valve which may be very readily adjusted to deliver fluid at any desired pressure.

Another object is to provide a valve which 25 may be positively closed without disturbing the adjustment thereof.

The invention consists essentially of a body having inlet and outlet passages, and two plungers mounted at opposite ends of a rocking arm. One of these plungers, located adjacent the inlet, is much smaller than the other and is arranged to control the admission of a high pressure fluid to the pressure reducing passages. The other plunger is spring pressed to normally maintain the valve full open for the entrance of high pressure fluid, but is so much larger in area than the smaller plunger that the pressure of low pressure fluid thereon will move the same to operate the small plunger and regulate the admission of high pressure fluid. Means are provided for regulating the constant load on the large plunger, and for positively operating the small plunger to entirely cut off the admission of 45 high pressure fluid.

In the drawings which illustrate the invention:—

Figure 1 is a vertical longitudinal sectional view of the valve.

50 Fig. 2 is a horizontal section on the line 2—2, Fig. 1.

Referring more particularly to the drawings, 11 designates a body forming two cylindrical chambers 12 and 13 respectively arranged axially parallel. Inlet and outlet

passages 14 and 15 are provided communicating respectively with the chambers 12 and 13, which communicate in turn with one another through a passage 16.

A hollow cylindrical member 17 is positioned co-axially with the chamber 12, and is provided with a seat 18 surrounding an opening 19, which opening forms the only communication between the inlet 14 and chamber 12. A plurality of small radially disposed ports 20 are provided through the wall of the member 17 above the seat 18, the total area of said ports being preferably greater than the area of the aperture 19.

A plunger 21 is mounted in the seat member 17 and is adapted to open and close the ports 20 upon reciprocation. This plunger is diametrically slotted at its upper end in vertical and horizontal planes to form a socket 22 for the reception of one end of a rocking lever 23, pivoted intermediate its ends on a pin 24. The opposite end of this lever engages a smaller socket 25 formed in the stem 26 of a plunger 27 operating in the chamber 13. The lower end of the spindle 26 is reduced in diameter, as shown at 28, and is reciprocatably mounted in a tubular guide 29, the lower end of which is provided with a suitable aperture 30 in order to prevent the spindle acting as a dashpot and retarding movement of the plunger 27. Each end of the lever 23 is provided with horizontally disposed trunnions or pins 31, which operate in the horizontal slots of the plunger 21 and spindle 26, while the lever ends oscillate in the vertical slots.

The upper end of the chamber 12 is closed by a cap 32, through which a screw threaded spindle 33 operates to regulate the maximum rise of the plunger 21 or to hold the same 95 positively down on its seat 18, and thus close the ports 20. The upper end of the chamber 13 is closed by a cap 34, within which a spring 35 of suitable strength is mounted. This spring is held in compression between 100 the plunger 27 and a washer 36 mounted on the lower end of a spindle 37 operating in the cap. Suitable apertures 38 are provided in the cap 34 for the entrance and expulsion of air, so that movement of the plunger 27 will not be interfered with. It will thus be seen that the spring 35 operates to normally hold the plunger 27 down on its seat 39. In order to render the plunger 27 fluid tight, a suitable number of rings 40 may be provided 110

in the circumference thereof bearing against the inner surface of the chamber.

It will be readily seen that the plunger 27 is much larger in area than the plunger 21, 5 and that the plungers are connected to the lever 23 approximately equidistant from the pivotal point, so that comparatively low pressure beneath the plunger 27 will raise the same and through the medium of the 10 lever 23 balance a very much greater pressure beneath the small plunger 21. The spring 35 restricts the upward movement of the large plunger, but the difference in size between the two plungers is so great that a 15 small pressure under the large plunger will still balance a high pressure under the small plunger. The amount of pressure required under the large plunger may be regulated by adjusting the compression of the 20 spring 35.

The operation of the device is extremely simple. Fluid at high pressure enters the valve through the passage 14 and flows through the aperture 19, and presses upwardly on the small plunger 21, thus drawing down the large plunger 27 with the assistance of the spring 35. The fluid then flows through the ports 20, expands within the chamber 12, and flows through the passage 16 into the chamber 13, and out through the outlet passage 15. This expansion of the fluid causes a great reduction in the pressure thereof. The low pressure fluid flowing into the chamber 13 presses upwardly on the plunger 27 against the spring 35, and tends to drive same up and thus depress the plunger 21 and close the ports 20. The compression of the spring 35 having been set to deliver fluid at a certain pressure, 25 for example, ten pounds, will hold the plunger 27 stationary against a ten pound pressure. If the pressure rises, the plunger will be forced up against the spring and thus depresses the small plunger 21, so that less 30 high pressure fluid is admitted. If, however, the pressure falls below ten lbs. the 35 spring will depress the large plunger, so

that the small plunger rises and admits more high pressure fluid.

The advantages of this valve are obvious, 50 as when once set it will adjust itself to variations of the high pressure fluid and maintain a delivery of fluid at a uniform low pressure. The uses of such a valve are too numerous to be enumerated, but it may be 55 stated that this valve has a particular advantage for steam heating, more particularly the heating of railway cars. When the train is nearing a terminal point, the spindles 33 on the individual cars are screwed down, 60 thus permanently closing the ports 20. The steam in the coils will repeatedly condense and drain back to the valve from where the water of condensation may be removed through an automatic trap attached for example at 41. It will thus be seen that merely cutting off the steam operates the drain automatically. If it is found impossible to obtain a single spring sufficiently strong for all 65 requirements, several springs may be used 70 simultaneously, or conversely, if it is found that a single spring strong enough for the maximum requirements of the valve is too stiff for minimum requirements, the heavy 75 spring may be readily exchanged for a lighter, or a number of springs used and one or more removed for low pressure use.

Having thus described my invention, what I claim is:—

In a device of the character described, a 80 body, a pair of plungers therein, cross-shaped slots formed diametrically in said plungers, a rocking lever pivoted to the body and having its ends projecting into said slots and operable in the vertical arms 85 of the slots, and lugs on the ends of said lever engageable in the latter portions of said slots.

In witness whereof, I have hereunto set my hand, in the presence of two witnesses. 90

ALFRED F. MURPHY.
